UNITED STATES PATENT OFFICE.

LAWSON G. HUNTINGTON, OF NEW YORK, N. Y., AND ROBERT J. ARMOUR,
OF NEWARK, NEW JERSEY.

SIGNAL LAMP OR LANTERN.

SPECIFICATION forming part of Letters Patent No. 490,770, dated January 31, 1893.

Application filed December 27, 1890. Serial No. 376,150. (No model.)

To all whom it may concern:

Be it known that we, LAWSON G. HUNTINGTON, residing in the city, county, and State of New York, and ROBERT J. ARMOUR, residing at Newark, in the county of Essex and State of New Jersey, citizens of the United States, have invented a new and useful Improvement in Signal Lamps or Lanterns, of which the following is a specification.

- 10 Our invention relates especially to lamps or lanterns bearing lenses, and has for its object the provision of a perforated air distributing plate, which may be removed for the purpose of cleaning, &c.
- 15 To attain the desired end, our invention consists essentially in a perforated plate, arranged to fit the body of the lamp, below the lenses, between the air passages through the lamp body, and the burner, said plate being arranged to receive the removable oil pot, and being either supported by a ledge formed or attached to the body of the lamp, or by a ring or cup into which the oil pot fits, all of which will be hereinafter first fully described, and
- 25 then pointed out in the claims.

In the drawings, Figure 1 is a vertical, central sectional view of a lamp wherewith our invention is employed, and Fig. 2 is a plan view of the perforated plate, on an enlarged scale, shown as removed from said lamp body. Fig. 3 is a vertical central sectional view of a square lamp, having the opening in the side, and Fig. 4 is a plan view of the perforated plate and oil pot, shown as removed from said lamp body.

Like letters of reference, wherever they occur, indicate corresponding parts in all the figures.

A is the lamp body, provided with lenses, B. C is the top of the lantern, either hinged, as in Figs. 1 and 2, or secured to the side walls, as in Figs. 3 and 4.

D is the carrying bail.

E is the bottom of the lamp body, provided with a supporting skirt, F.

G (Fig. 1), is a circumferential bead, formed in the body A.

In the construction shown in Figs. 1 and 2, the removable perforated plate, H, has an

opening in its center, and I is a cup or ring 50 upon which said plate rests, or to which it is secured, for the purpose of supporting it; or the ring or cup may be dispensed with, and the outer edge of the plate rest upon the bead G.

J is a removable oil pot, which passes through the opening in plate H, or is mounted upon the plate, which may be so arranged as to hold the pot in position.

In the form of lamp shown in Figs. 3 and 4, 60 the body is provided with ledges or beads, M, which receive and support the removable perforated plate, H, and N are strips or ways, fixed upon the perforated plate, arranged to receive the removable oil pot, J.

When constructed and arranged in accordance with the foregoing description, the advantages of our arrangement will be obvious.

Heretofore, in lamps or lanterns of the class to which our invention is applied, the perforated plate has been fixed and immovable, being secured to the walls of the lamp; dirt, dust &c would enter the lamp beneath such plate, and drop upon its upper surface; oil would also flow, over and through the perforations, until finally the air requisite to support combustion would be prevented from passing through the plate. In cleaning the same, only the top within the lamp body could be reached, and the under side of the plate 70 could not be cleaned at all. By our invention, all this difficulty is overcome; the oil pot and plate can both be instantly removed, and all of the parts quickly and effectually cleaned.

Having now fully described our invention, what we claim as new therein, and desire to secure by Letters Patent, is:—

1. The combination with a lamp or lantern body bearing lenses and having a closed bottom, of a removable perforated plate supported within the lamp body, as set forth, and arranged to hold the oil pot in place, substantially as shown and described.

2. The combination with a body of a lamp 95 of the character herein specified, having a closed bottom, of a removable perforated plate supported therein and having a central open-

ing in which is seated a removable oil pot, substantially as shown and described.

3. In a lamp of the character herein specified, having a closed bottom, the combination
5 with the removable perforated plate having an opening in its center, and a supporting ring or cup, of a removable oil pot seated in

said ring or cup, substantially as shown and described.

LAWSON G. HUNTINGTON.
ROBERT J. ARMOUR.
